REFRIGERATOR UNIT

Willard A. Gebhardt and Edwin J. Radtke,
Milwaukee, Wis.

Application December 28, 1936, Serial No. 117,913

2 Claims. (Cl. 62—129)

This invention appertains to refrigeration, and more particularly to a cooling unit with novel means for circulating a constant volume of cool air through a refrigerator.

5 One of the primary objects of our invention is to provide a refrigerating unit of a compact and simple order, which will occupy a minimum amount of space, and which can be advantageously disposed in a refrigerator to insure a 10 maximum amount of storage space in said refrigerator.

Another salient object of our invention is to provide a cooling unit embodying a rotary air blower, with novel means for leading the air past 15 a refrigerating unit, so as to bring about a constant circulation of cool air in said refrigerator.

Another object of our invention is to provide novel means for subjecting the air to a water film as the air flows past the refrigerating unit, 20 whereby to bring about the washing of the air and the humidifying thereof, so as to prevent shrinkage and discoloration of meat, and so forth, and to prevent undue collection of frost on the refrigerating unit.

25 With these and other objects in view, the invention consists in the novel construction, arrangement, and formation of parts, as will be hereinafter more specifically described, claimed, and illustrated in the accompanying drawings, in 30 which drawings:

Figure 1 is a perspective view of our improved cooling unit showing the same suspended from the ceiling of a refrigerator.

Figure 2 is a top plan view of our improved 35 cooling unit.

Figure 3 is a longitudinal section through the cooling unit taken on line 3—3 of Figure 2, looking in the direction of the arrows.

Figure 4 is a fragmentary, transverse section 40 taken on line 4—4 of Figure 2, looking in the direction of the arrows.

45 Referring to the drawings in detail, wherein similar reference characters designate corresponding parts throughout the several views, the letter C generally indicates the improved cooling unit, and R a refrigerator in which the same can be disposed. The refrigerator R can be of any preferred type, and of the character generally used in meat markets, and the like. As illustrated, the refrigerator includes a top wall or roof 5, and end and side walls 6 and 7.

50 The improved cooling unit C comprises a sheet metal body 10, which can be suitably treated to withstand deterioration from rust and the like. 55 This body 10 includes longitudinally extending,

spaced, parallel side walls 11, end walls 12 and 13, and a bottom wall 14. Extending transversely across the body is a partition wall 15 defining a chamber 16 for the blower element 17 and a chamber 18, the purpose of which will be later 5 set forth.

The blower element 17 is preferably of the rotary-wheel impeller type having a row of circumferentially extending peripheral vanes 19. Air is sucked in through the side wall of the 10 blower, and is expelled through an opening in the outer wall of the blower casing. The blower outlet can have communicating therewith a flared distributor mouth 20, which extends through the lower end of the partition wall 15. It is to be 15 noted that the top of the body is open, and that the lower wall 14 thereof in rear of the fan or blower 17 is provided with an air inlet opening 21.

The body can be reinforced in any preferred 20 manner, and has riveted or otherwise secured thereto at spaced points transversely extending strips of angle iron 22. Suspension bolts 23 depending from the roof 5 of the refrigerator extend through the angle irons. 25

Arranged within the compartment 18 in spaced relation to the bottom wall 14 of the body is a drip plate 24, having punched therein a plurality of drip openings 25. The portions of the metal around the walls of the drip opening are struck 30 up, as at 26, so as to form a series of nipples, which extend slightly above the upper face of the drip plate. That portion of the compartment 18 below the drip plate constitutes a drip pan, and an over-flow pipe 27 communicates with said drip 35 pan for leading water therefrom. That portion of the compartment 18 above the drip plate has mounted therein in any suitable manner a refrigerating unit 28, and this unit can be of any desired character or make best suited for the purpose intended. 40

It is to be noted that the ends of the drip plate 24 have formed thereon upstanding side flanges 29, which are riveted or otherwise secured to the end wall 13 of the body and the partition wall 15. The side longitudinal edges of the drip plate have formed thereon depending flanges 30, which rest on the upper face of the bottom wall 14 of the body, and these flanges 30 serve as means 45 for supporting the drip plate and reinforcing the body. 50

We also preferably arrange in the compartment 18, above the drip plate 24, longitudinally extending guard plates 31 for the refrigerating unit, and 55

these guard plates are arranged in spaced parallel relation to the side walls 11 of the body.

In use of our improved cooling unit, the same is suspended from the ceiling of a refrigerator 5 in the manner described and shown in Figure 1, and a constant volume of air will be forced by the blower 17 in the compartment 18 below the drip plate 24. This air will flow through the openings 25, and will be equally distributed over 10 the refrigerating unit 28. The air flowing past the refrigerating unit will strike the ceiling or roof of the refrigerator, and will then be forced downwardly completely around the refrigerator. Water dripping from the refrigerating unit 28 will 15 collect on the drip plate 24, and due to the formation of the nipples 26, a constant film of water will collect on the upper surface of said drip plate. Hence, the air flowing through the openings will be cleansed and humidified. This is highly im- 20 portant as the humidified air prevents loss of meat by shrinkage, and otherwise acts to correctly keep food stored in the refrigerator.

When the water rises above the nipples 26, the same will flow into the drip pan, and the air blowing 25 over the surface of the water in the drip pan will also pick up moisture therefrom. As set forth, when the water reaches a certain height in the drip pan, the same overflows into the pipe 27.

30 From the foregoing description, it can be seen that we have provided an exceptionally simple and compact cooling unit, which will permit a constant volume of humidified cool air to be distributed throughout the refrigerator.

35 When the ceiling is interrupted, or positioned at such distance from the equipment that it cannot be used for a deflector, as shown in Figure 3 of the drawings, we attach a deflector plate 32, which deflector plate is connected to the refrigerating unit 28 by straps 33.

Changes in detail may be made without departing from the spirit or scope of our invention, but what we claim as new is:

1. A cooling unit for a refrigerator comprising a body adapted to be disposed in close proximity to the ceiling of the refrigerator, a transversely extending partition in said body defining a pair of compartments, a refrigerating unit in one of said compartments, a drip plate in the last mentioned compartment below the refrigerating unit having a plurality of openings therein, the portion of the last mentioned compartment below the drip plate constituting a drip pan, an overflow pipe for said drip pan, and a rotary air blower arranged in the other compartment for forcing air into the first compartment over the water in the drip pan and through the openings in the drip plate past the refrigerating unit, said drip plate 15 having nipples extending around the openings therein, whereby to permit a film of water to collect on the drip plate.

2. A cooling unit for a refrigerator comprising a body adapted to be disposed in close proximity to the ceiling of the refrigerator, a transversely extending partition in said body defining a pair of compartments, a refrigerating unit in one of said compartments, a drip plate in the last mentioned compartment below the refrigerating unit 25 having a plurality of openings therein, the portion of the last mentioned compartment below the drip plate constituting a drip pan, an overflow pipe for said drip pan, a rotary air blower arranged in the other compartment for forcing 30 air into the first compartment over the water in the drip pan and through the openings in the drip plate past the refrigerating unit, said drip plate having nipples extending around the openings therein, whereby to permit a film of water to 35 collect on the drip plate, said body being open at its top, and having an opening in its bottom in the compartment receiving the blower.

WILLARD A. GEBHARDT. 40
EDWIN J. RADTKE.
